UNITED STATES PATENT OFFICE.

CARL M. HEDMAN, OF CHICAGO, ILLINOIS, ASSIGNOR TO HEDMAN MANUFACTURING COMPANY, OF CHICAGO, ILLINOIS, A CORPORATION OF ILLINOIS.

CHECK PROTECTOR.

Application filed June 9, 1924. Serial No. 718,687.

My invention relates to check protectors, one object of the invention being the provision of improved means for perforating the area of a check upon which the payee's name is written, and especially for effecting such perforation by the same actuating movement which prints the amount upon the check. The perforating means of my invention is peculiarly advantageous in that 10 type of check protector wherein the inking swab in travelling to and from the type must pass over that area of the check bearing the payee's name. A further object is to provide the perforating means with an im- 15 proved paper lifting element for forcing the check from the perforating member to permit its ready withdrawal.

Another object of my invention is the provision of an improved full stroke mechanism whereby the operation of the device must be fully completed in order that it may return to its normal position, thus insuring that the printing and perforating of the check is completely accomplished before the 25 check may be withdrawn.

These and further objects and features of my invention are set forth in the following description of a particular embodiment thereof, which is illustrated in the accompanying drawings, wherein

Figure 1 is a transverse vertical section of my check protector, which may be considered as taken along the line 1—1 of Figure 4;

Figure 2 is a detail of the full stroke mechanism when the actuating handle has been partly depressed;

Figure 3 is a fragmentary transverse section somewhat similar to Figure 1, which may be considered as taken on the line 3—3 of Figure 4;

Figure 4 is a fragmentary longitudinal vertical section taken on the line 4—4 of Figure 3; and

Figure 5 is a plan view of a check printed and perforated by the check protector shown.

I have illustrated my invention as embodied in a check protector of the general form disclosed in Patent No. 1,197,279, 50 issued September 5, 1916, to Douglas F. Fesler. The check protector is mounted upon a stamped base 10, within which is secured a casting in the form of a block 11 for supporting the platens and other stationary parts. Upon the base are rigidly sup-

ported a pair of side plates 12 connected by a pivot rod 13. By means of the pivot rod 13 a movable casing, comprising end walls 14 and a back or cover plate 15, is pivoted on the base, and is urged upwardly or counter-clockwise by stiff loop springs 16. A shaft 17 extends between and is supported by the end walls 14 of the casing, the shaft rotatably supporting a plurality of spaced type sectors 18 arranged for the respective digits of the amount to be printed, the arcuate periphery of each sector being provided with a series of numeral types 19 in ascending order. These type sectors may be substantially the same as those disclosed in the 70 above-mentioned patent, and the type themselves may be similar to those disclosed in Patent No. 1,338,645, issued April 27, 1920, to Douglas F. Fesler and Herbert R. Hedman. An upper arcuate portion of each 75 type sector is provided with a plurality of notches 20. Pawls 21 mounted on a cross shaft 22 of the casing and pressed by loop springs 23, co-operate with the notches of the respective type sectors to hold the desired 80 numeral of each in printing engagement with the platen.

The base block 11 is provided with a suitable slot for the reception of the platen bar 24, the bar being supported at its bottom by 85 a plate 25 secured, as by the screws shown, to the lower side of the forward end of the base block 11. For a considerable distance inwardly from the forward ends of the stationary side plates 12, their lower edges are 90 spaced upwardly from the top surface of the base stamping 10, forming a deep slot into which the check may be inserted with its ends projecting outwardly at either side of the device. The check thus rests upon the 95 platen bar 24 and at some distance below the normal position of the type sectors.

The actuating lever 26 is pivoted upon the cross pin 27 of a post 28 of channel shaped cross section which rises from the base 100 block 11. Adjacent its pivot point, the actuating lever 26 carries a cam plate 29, the profile of which engages a roller 30 suitably journaled on the back plate 15 of the movable casing. Downward pressure on the 105 lever 26 forces the casing downwardly rather rapidly about its pivot 13 on the base until the type sectors engage the paper and start to force it against the perforating surface of the platen bar 24. 110

At this point, the roller 30 reaches the more steeply inclined surface 29' of the cam plate 29 so that during the remainder of its downward movement the lever 26 forces the casing only a short distance but with a greatly increased leverage. The mating surfaces of the type sectors and of the platen bar 24 are thus forced together with the paper between them, printing the amount of the check and simultaneously perforating the paper along the outline of the numerals.

For inking the type previously to the printing and perforating operation, the form of check protector here shown is provided with an inking swab 31 carried upon a movable frame or carriage 32 which extends across the lower side of the type sectors and between the stationary side plates 12. At each end the swab carriage 32 is provided with spaced pins 32' which extend into slots 33 in the side plates. The slots in general parallel the lower edges of the side plates so that the carriage may be brought to a rearward position where it is out of the way of the type during the printing and perforating operation. When at its rearward position, the swab 31 is adapted to engage one of a pair of ink supplying rollers 34. The forward ends of the slots are so conformed that they raise each of the pins upwardly somewhat to bring the swab into contact with the type sectors during the normal position of the device. As the carriage is moved along the slots 33 toward its rearward position, its first movement is downward to bring the swab away from the type.

For reciprocating the carriage 32 so that the inking swab is moved away from the type previous to the printing and perforating operation, I provide at each side of the device a link 35 connected with the free end of a pinion arm 36 pivoted on the shaft 17, the toothed portion of which engages an arcuate rack 37 on the respective side plate 12. When the actuating lever is depressed, the movable casing, and hence the shaft 17, are moved downwardly. The pinion arm 36 then rolls along the rack 37 to swing the free end of the arm rapidly in a clockwise direction and, through the link 35, to push the swab carriage along the slots 33 to its rearward position beneath the ink supplying rollers 34.

In order fully to protect a check, it is necessary not only that the amount be so written that it cannot be altered, but also that it be impossible to change the payee's name. To this end, I provide a perforating bar and cooperating platen for perforating the area of the check upon which the payee's name is written, and perform this perforating operation substantially simultaneously with the printing and perforating of the

amount numerals. The base block 11 is provided with a second slot extending parallel to and but a short distance rearwardly of the slot in which the type platen 24 is secured. In this second slot is secured a 70 perforating bar 38 similarly supported at its bottom by the plate 25. The perforating bar 38 on its upper surface is provided with a plurality of upwardly extending conical points arranged in longitudinal and 75 transverse rows, as indicated by the perforated impression left on the check of Figure 5.

The platen 39 which co-acts with the perforating bar 38 is formed adjacent the forward edge of a horizontal plate 40 extending between the stationary side plates 12 and yieldingly supported by a spring-like sheet of metal 41, to the forward edge of which the plate 40 is secured. The rearward portion of the sheet 41 is riveted or 80 spot welded to the top of the base stamping 10, the sheet being so sprung that it urges the plate 40 upwardly and away from the perforating bar 38. The platen 39 carries a plurality of parallel cuts, preferably disposed transversely as shown in Figure 5, 85 forming ridges for pushing the paper on either side of the rows of points on the bar 38, so that the points perforate the paper of the check. In employing the term "perforate" I contemplate that the perforating need not be complete, and that the perforating elements may merely sufficiently indent the paper of the check to prevent the subsequent changing of the payee's name. 90

To press the platen 39 against the check and the perforating bar, it is obviously desirable in a check protector of the type shown to apply the force from above the plate 40. Whatever means is employed for this purpose, it will be noted, must provide for the passage of the ink swab and its carriage before the perforating of the payee's name. I have solved this problem by providing a pair of fingers 42 mounted 100 on the pivot rod 13 of the base. These fingers 42 are urged upwardly by a tension spring 43 connected between the cross pin 44, which extends between the fingers, and the following described pin 45. The pivoting of the platen actuating fingers 42 on the pin 13 in common with the side walls 14 of the movable frame insures their accurate operating relation when assembled which might otherwise be impaired were 110 the fingers pivoted to the post or on another pivot pin.

The spring 43 serves to hold the fingers 42 up sufficiently to permit the swab and its carriage to pass between them and the plate 40 before the fingers contact the plate to press it against the perforating bar. When the operator depresses the handle 26 and thereby moves the casing downwardly about its pivot pin 13, a third cross pin 45, which 120

forms the stationary anchorage for the pawl springs 23, contacts a roller 46 which extends between and is journaled by the fingers 42. The cross pin 45 then forces the 5 fingers 42 downwardly until they contact the plate 40 and press the platen 39 down upon the paper to force the latter against the perforating bar 38. It will be noted, however, that the initial movement of the 10 casing results in the pinion arm 36 sending the swab to its rearward position, while the roller 46 of the fingers is not engaged until after the swab has been removed from its proximity to the plate 39 and the fingers 42. 15 When the check protector is in the normal position of Figure 3, the bottom of the swab carriage 32 acts as a stop to limit upward movement of the plate 40 by the spring metal sheet 41. The slots 33, it will be remembered, are so arranged that the initial 20 movement of the swab is downward so that when the lever is first depressed, the carriage will itself lower the plate 40 somewhat before the fingers 42 contact it for more 25 tightly pressing the platen against the perforating bar.

The perforating bar 38 is provided, along the longitudinal medial line of its perforating surface, with a narrow slot 47 within 30 which is vertically reciprocable a lifting strip 48 having, in the form shown in Figure 4, three downwardly extending legs 49 passing through suitable vertical slots 47' in the bar 38 and in the plate 25. The lower 35 end of each leg 49 is engaged by a spring finger 50 formed integrally with a strip 51 extending along the length of the plate 25 and secured thereto as by the previously mentioned screws. The spring fingers 50 are 40 so sprung that they tend to urge the lifting strip 48 upwardly. Upward movement of the lifting strip is shown as limited by the spring fingers when they contact the bottom surface of the plate 25.

45 A check to be imprinted is slid in a transverse manner into the device from the forward end, a sheet metal bridge 24' preferably being provided to carry the leading edge of the check up to the top of the platen bar 24 to prevent its being caught thereby. When fully inserted the check rests in part upon the upper edge of the lifting strip 48. As the lever 26 is pressed downwardly, the platen 29 will be pressed by the fingers 42, 50 as previously explained, to force the paper downwardly over the perforating points of the bar 38. Under this pressure, the spring fingers 50 will yield to permit the strip 48 to be forced to the bottom of the slot 47 where it does not interfere with the functioning of the co-operating perforating bar and platen. When the actuating stroke of the lever has been completed and the springs 60 16 have again raised the casing, the spring fingers 50 will press the lifting strip 48 up-

wardly to pull the paper of the check off the perforating points. Because the strip 48 is within the area covered by the points, it tends to lift the paper longitudinally of the points and in consequence distortion or 70 tearing of the check is avoided. Were it not for a lifting device of this kind, the check would be locked against lateral or longitudinal movement by the points and considerable difficulty would be encountered in removing the check from the device. The perforations effected in the paper by the printing type and the platen bar 24 are not so deep, and hence less difficulty is encountered in lifting the paper from the platen. 80

The previously mentioned full stroke mechanism will now be described. Rearwardly of its pivot about the pin 27, the actuating lever 26 is provided with a pair of dogs 54 and 55 pivoted at their upper ends 85 by a common pivot pin 56. These dogs 54 and 55 are placed side by side, that nearest the reader being provided with a slot 57 through which extends a cap screw 58 secured in the dog 55. A spring washer 59 provides sufficient friction between the dogs so that they tend to move together. At their lower ends the dogs are provided with diverging cam surfaces, between which enters the upper end of a bracket 47 which is secured to the post 28. The movement of lever 26, as normally urged upwardly by the force of the loop springs 16 against the casing, is limited, and in turn limits the upward movement of the casing, by a cross pin 48 100 which is contacted by the rearward end of the lever 26. As the operator depresses the lever 26, the diverging cam surface of the dog 55 rides along the upper edge of the bracket 47, permitting the dogs to swing 105 downwardly, the cammed left hand edge of the dog 54 then contacting the cross pin 49 in the post 28. It will be seen from Figure 1 that shortly before the casing is depressed sufficiently to start the actual perforating of the paper, the cross pin 49 will reach the portion 54' of the cammed edge of the dog 54, which portion is substantially arcuate about the pivot pin 56. Gravity will then swing the dogs to the position of Figure 2, 110 where the portion 54' will overlie the cross pin 49 to prevent the return of the lever 26 to its normal position.

When in this position, swinging of the dogs by gravity will be limited by the cross pin 48 which is contacted by the left hand edge of the dog 55. As the lever is further depressed to complete the printing and perforating, the cam shoulder 54'' engages beneath the cross pin 48 to cam the dogs outwardly, that is, to the right. The right hand edge of the dog 55 will then contact the upper edge 28' of the opening in the web of the post 28. Pressure against the cross pin 48, however, continues to cam the dog 115 120 125 130

54 after the dog 55 is stopped, so that they are moved relatively until the screw 58 is passed to the end of the slot 57. When the operator releases the lever 26 and the latter is forced back to its normal or upper position, the cross pin 48 bearing against the left hand edge of the dog 55 will hold both dogs from swinging inwardly, that is, to the left, and since the dog 54 has been moved to further overlie the dog 55 the cam portion 54' 10 will no longer overlie the cross pin 49. This permits the dogs to descend so that the cross pin 49 comes opposite the cammed edge of the dog 54 intermediate the portion 54' and the shoulder 54''. The upper edge of the bracket 47, as the dogs descend, enters between the outwardly cammed ends of the dogs again to spread them apart to the normal position of Figure 1.

20 I have, in the foregoing mechanism, provided a reliable full stroke mechanism which prevents the incomplete printing or perforating of a check. This is especially desirable since it would be very difficult to re-insert a check which had been partially perforated and faintly printed into the device and so position the check that the printing and perforating would exactly register with the previous printing and perforating so that the check would not look mutilated or altered on its face. This full stroke mechanism is so arranged that in case anything should go wrong with it—for instance the dogs, through lack of proper lubrication fail 30 to pivot freely, or should the dogs be wholly removed from the device—the check protector will work fully as well as though the full stroke mechanism had not been incorporated in its original design.

40 I prefer that the cam plate 29 be adjustably fixed to the lever 26 as by pivoting it about the bolt 60 passing between the flanges of the channel shaped lever 26, the plate being adjustable to swing about its pivot by a set screw 61 which contacts the rear edge of the plate. The position of the casing, and hence the type sectors and perforating platen relative to the position of the full stroke mechanism, may be correctly adjusted by 45 the set screw 61.

50 While I have shown but this specific embodiment of my invention, I contemplate that many changes may be made without departing from the scope or spirit of my invention.

55 I claim:—

1. In a check protector the combination of a base, selective amount type movably supported upon said base, a type platen therefor on said base, co-operating perforating platen members, one of said members being secured to the base, spring means for supporting the other of said members from said base a spaced distance above said one member, and common means for moving said

type against said platen to imprint the amount upon a check and for bringing said members together against the force of said spring means to perforate the area of the check upon which the payee's name is 70 written.

2. In a check protector the combination of a perforating bar having a number of points thereon, a platen for said bar, means for bringing said bar and platen together to 75 perforate an area of a check, a lifting member disposed within the area covered by said points for forcing the check from said points after the perforation thereof, a recess in said bar for the reception of said member, and means urging said member from said recess to lift the check, said means permitting the member to be depressed in said recess when said type and platen are brought together.

3. In a check protector the combination 85 of a perforating bar having a multiplicity of points thereon, a platen for said bar, means for actuating said bar and platen to perforate an area of a check, a lifting member disposed within the area covered by said 90 points, a recess in the bar for the reception of said member, and spring means urging said member from said recess for lifting the check from said points after perforation 95 thereof, said member being engaged by said platen, when the bar and platen are actuated, to depress said member in said recess.

4. A check protector comprising a bar having a number of perforating points thereon, arranged over an elongated area thereof, a platen for said bar, means for bringing said bar and platen together to perforate an area of a check, a lifting strip disposed within and extending longitudinally of said area 100 of the bar, a slot in said bar for the reception of said strip, spring means for urging said strip outwardly for lifting the check from the points after perforation of the check thereby, said spring means yielding when said bar and platen are brought together for 105 permitting said strip to be depressed in said slot.

5. In a check protector having a base, means for perforating an area of a check comprising a bar secured in said base and 110 provided on its face with a multiplicity of perforating points, a platen for co-operating with said points, means for forcing said platen against said points to perforate said area, a slot in the face of said bar, a lifting strip mounted for movement in said slot, a leg on said strip extending below said bar, spring means at the back of said bar engaging said leg for urging said strip out of 115 said slot toward the ends of said points, said spring means yielding when said platen is forced against said bar to permit said strip to be depressed into said slot.

6. The combination of a perforating 120 member having a face provided with a plu-

rality of perforating points, a platen therefor, means for forcing said platen against said points to perforate a portion of a check, a slot in the face of said member 5 between said points, holes in said member extending from said slot to the back of said member, a strip mounted for movement in said slot transversely of said face, legs on said strip extending through said 10 holes, and spring fingers at the back of said member contacting said legs for urging said strip outwardly from said slot to force the check off from said points, said spring fingers yielding when said platen is 15 forced against said member to permit said strip to be depressed in said slot below said points.

7. In a check protector the combination of indenting type, a platen therefor, actuating means for bringing said type and said platen together with a check therebetween for forming indentations in the check, and a full stroke mechanism effective at the commencement of such indentation for preventing the separation of said type and 25 platen before the completion of such indentation.

8. The combination with a check protector comprising a stationary frame, a movable frame mounted thereon, type mounted on one of said frames, a type platen mounted on the other of said frames, and an actuating lever mounted on said stationary frame for bringing said type and 35 platen together upon its actuating stroke to imprint a check, of a full stroke mechanism operating between said stationary frame and on said lever for precluding the return stroke of said lever before the completion of such imprinting of the check 40 upon its actuating stroke.

9. In a check imprinter the combination of an actuating lever therefor, a pair of members mounted for movement by said lever and normally moving together, means for guiding one of said members in its said movement by said actuating lever, co-operating stop means operative at the commencement of the imprinting for preventing the return movement of said lever, means operative when the imprinting is completed for relatively moving said members from a normal relation to move said stop means out of operative relation, and 55 means, operative after said lever starts on its return stroke, for again relatively moving said members to their normal relation.

10. In a check protector, the combination of an actuating lever therefor which 60 imprints the check upon its actuating stroke, a guided dog and a stop dog pivotally mounted on the lever, friction means for causing said dogs to move together, means for confining the swinging of the 65 guided dog about its pivot on the lever,

fixed stop means, catch means on the stop dog for co-operating with the stop means to preclude the return stroke of the lever before the completion of such imprinting, means for engaging the stop dog to move 70 it relatively to the guided dog and render the stop means inoperative when the imprinting of the check is completed, and means for returning said dogs to their previous relative positions before the commencement of the imprinting on the succeeding actuating stroke of the lever. 75

11. Means for insuring the complete imprinting of a check by a check protector, comprising a lever therefor, the actuating 80 stroke of which imprints the check, a guided member and a catch member mounted for movement by said lever and normally moving together, means for confining the movement of the guided member, stop means operative during the imprinting of the check for preventing the return stroke of said lever, means operative when the imprinting is completed for relatively moving said members to render 85 said stop means inoperative and means for subsequently returning said members to their normal relation. 90

12. Means for insuring the complete imprinting of a check by a check protector, 95 comprising a lever therefor, the actuating stroke of which imprints the check, a frame, a dog pivotally mounted on the lever, a guide member for the dog also mounted to pivot on the lever, friction means causing the member normally to swing with the dog about its pivotal mounting, a stop on the frame, a shoulder on the dog for engaging the stop to prevent the return stroke of the lever, co-operating cam means on the dog and on the frame engaging at the completion of the actuating stroke of the lever for moving the shoulder out of engagement with the stop, the member at such time engaging the frame to prevent swinging of the member and thereby causing the dog and member to be relatively moved, the member thereafter engaging the frame for holding the shoulder out of engagement with the stop to permit the return stroke of the lever, and means on the frame for relatively moving the dog and the member back to their relative relation at the end of their movement by the return stroke of the lever. 100 110 115

13. A check protector comprising a base, a movable frame pivoted thereto, selective type carried on the frame, a platen on the base for co-operating with the type to imprint a check, a pair of co-operating perforating members, one of which is secured to the base and the other suspended therefrom, an actuating lever for moving the frame to bring the type and platen together, and a second lever pivoted on the base and engaging said suspended member when the 120 125 130

actuated lever is operated for bringing the co-operating perforating members together to perforate a check at a region other than that imprinted by the type.

14. A check protector comprising a base, a movable frame, a pivot pin for rotatably mounting the frame upon the base, selective type carried by the frame, a platen on the base for co-operating with the type, an actuating lever swinging the frame about the pivot pin for bringing the type and platen together to imprint a check, a pair of co-operating perforating members one mounted on the base and the other suspended there-
above, a second lever pivotally mounted on the said pin and adapted to engage the suspended member, and means for moving the second lever upon actuation of the first lever to engage the suspended member and force it against the base member for perforating an area of the check.

15. A check protector comprising a base, a movable frame, a pivot pin for rotatably mounting the frame upon the base, selective type carried by the frame, a platen on the base for co-operating with the type, an actuating lever for swinging the frame about the pivot pin for bringing the type and platen together to imprint a check, a pair of co-operating perforating members, one mounted on the base and the other suspended thereabove, a second lever for engaging the suspended member, means for moving the second lever upon actuation of the first lever to engage the suspended member and force it against the base member for perforating a region of the check other than that imprinted by the type, an inking swab for said type, and means for moving the swab into contact with the type between successive actuations thereof by the actuating lever and for moving the swab away from the type during such imprinting, the swab in such movements passing between the engaging portions of the depressing lever and the suspended member.

16. A check protector comprising a base, a movable frame mounted thereon, a co-

operating type and platen carried by the base and frame, an actuating lever for bringing the frame and base together to imprint a check, a pair of co-operating perforating members, one mounted on the base and one suspended thereabove, an element interposed between the lever and the suspended perforating member for bringing the two members together to perforate another area of the check upon the actuation of the lever, an inking swab, and means for moving the swab into contact with the type between successive actuations thereof by the lever and for moving the swab away from the type during the actuating stroke of the lever, the swab in one of such movements passing between the said element and the suspended perforating member.

17. In a check protector, the combination of type, a platen therefor, actuating mechanism to bring said type and platen into cooperative engagement, and means to prevent incomplete cooperation of said type and platen comprising a pair of pivotally mounted pawls frictionally engaging each other, means to move one of said pawls relative to the other upon the completion of the printing operation, and a stop engageable by one of said pawls to prevent the return movement of said actuating mechanism to normal position prior to the completion of the printing operation.

18. In a check protector, the combination of type, a platen therefor, operating means to bring said type and platen into cooperative engagement, a pair of pawls pivotally secured to said operating means, means for frictionally holding said pawls together, a stop engaging one of said pawls to prevent return movement of said operating means after a printing operation has been initiated, and means to move said pawl relative to the other of said pawls upon completion of the printing operation so as to prevent its engagement with said stop.

In witness whereof, I hereunto subscribe my name this 28th day of May, 1924.

CARL M. HEDMAN.
